US00D732574S

(12) **United States Design Patent**
Capela et al.

(10) **Patent No.:** **US D732,574 S**
(45) **Date of Patent:** **** Jun. 23, 2015**

(54) **DISPLAY SCREEN OR PORTION THEREOF
WITH ICON**

(71) Applicant: **Apple Inc.**, Cupertino, CA (US)

(72) Inventors: **Jay Christopher Capela**, Santa Cruz, CA (US); **Gary William Gehiere**, Santa Clara, CA (US); **Alexander Charles MacLean**, San Jose, CA (US)

(73) Assignee: **Apple Inc.**, Cupertino, CA (US)

(**) Term: **14 Years**

(21) Appl. No.: **29/435,713**

(22) Filed: **Oct. 26, 2012**

(51) **LOC (10) Cl.** **14-04**

(52) **U.S. Cl.**

USPC **D14/489**

(58) **Field of Classification Search**

(57) **CLAIM**

The ornamental design for a display screen or portion thereof with icon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen or portion thereof with icon showing our new design; and,

FIG. 2 is a front view of another embodiment thereof.

The broken lines around the Figures show a display screen or portion thereof and form no part of the claimed design.
